WEED KILLER

Peter Kilham, Barrington, R.I., assignor to Droll
Yankees Inc., Foster, R.I.

Filed Oct. 30, 1972, Ser. No. 302,263

Term of patent 14 years

Int. Cl. D8—99

U.S. Cl. D8—1

FIG. 1

FIG. 2

FIG. 3

FIG. 5

FIG. 1 is a front elevational view of a weed killer showing my new design, it being understood that the weed killer has the same appearance in rear elevation;

FIG. 2 is a side elevational view thereof;

FIG. 3 is a bottom plan view thereof;

FIG. 4 is a top plan view thereof; and

FIG. 5 is a perspective view of the weed killer in inverted position with a portion of the side wall broken away for purposes of illustration.

I claim:

The ornamental design for a weed killer, substantially as shown and described.
